EMILE STRAUB, OF EMMISHOFEN, SWITZERLAND

APPARATUS FOR STRETCHING THE MATERIAL FOR HANDKERCHIEF EMBROIDERY
IN THE SHUTTLE EMBROIDERY MACHINE

Application filed March 3, 1927, Serial No. 172,484, and in Switzerland March 3, 1926.

The present invention refers to apparatus for stretching the material for handkerchief embroidery in the shuttle embroidery machine. Material stretching devices with several frames secured on the machine frame are known, with which the whole surface of the individual handkerchief is stretched, which results in waste of space. Further it has already been suggested to stretch between rollers only the surface to be embroidered of each individual handkerchief, the remainder being wound on the two rollers. This has again the result that the space for disposal on the machine frame cannot be completely used, since for each handkerchief two rollers must be provided. Furthermore, on each handkerchief a certain width of material must be reserved for stretching, so that the embroidery cannot be worked as near as desired to the edge of the handkerchief. The edge must afterwards be cut off; there is an unused waste of material.

These disadvantages are obviated by the process according to the present invention in that between each two consecutively working needles an intermediate portion of a piece of material running in the direction of the row of needles is wound upon a shaft disposed perpendicular to the row of needles, so that between each two of these shafts a strip is left free for embroidery.

In the accompanying drawing is shown a practical example of the device for stretching the material, whereof;

Fig. 1 is an elevation of an embroidery machine,

Fig. 2 a piece of cloth to be stretched on a frame,

Fig. 3 an elevation of a part of a frame,

Fig. 4 a detail of Fig. 3 in side elevation,

Fig. 5 a detail of a shaft seen in the longitudinal direction of the machine frame,

Fig. 6 a detail of Fig. 5 to an enlarged scale in section,

Fig. 7 a detail of Fig. 3 seen in the longitudinal direction, of a shaft,

Figs. 8-10 sections through different positions of the shaft, and

Fig. 11 is a section through a second example of this shaft.

On the embroidery machine frame 1 (Fig. 1) are secured several frames by means of bars 3. These frames comprise longitudinal bearers 2 and cross bearers 4, which latter present a bent form (Fig. 4). On the longitudinal bearers 2 are provided rails 5 in which are rigidly secured parallel tubes 6 which possess slots running in their longitudinal direction towards the path of the shuttle. In these tubes are rotatably arranged shafts 7, which may have any suitable form, and are divided in their longitudinal direction into two symmetrical parts. On the ends of these shafts 7 are ratchet wheels 8 with which pawls 9 secured on the rails 5 and under the action of springs 10 can co-operate. The rotation of the shaft 7 is effected by means of knurled heads 11.

The shafts 7 can be either solid or hollow shafts, in which latter case (Fig. 11) a rubber insertion 12 is arranged in the hollow space.

The ends of the individual parts 7^a and 7^b of the shaft are inserted into a sleeve 14 on which also the ratchet wheel 8 and the head 11 are mounted. With the sleeve 14 is rigidly connected a semi-cylindrical part 13, for example soldered. The shaft 7^b can be clamped fast on this part 13 in the sleeve 14 with a screw, whereas the shaft-half 7^a, which is inserted in the sleeve 14 is removable.

The manipulation of the appliance is as follows:

A piece of material 16 (Fig. 2) is provided the length of which corresponds to as many handkerchiefs as there are embroidery spaces, i. e. the intermediate spaces between each two shaft members 7^b after removing the shaft-halves 7^a of a frame, the shafts being divided from one another with equal spaces therebetween so that between each two shafts as much material is provided as corresponds to one handkerchief. Upon inserting the shaft members 7^a the material is clamped fast and by rotation of the shafts 7 (Figs. 8-10) inserted in the tubes 6 a portion of the material of each handkerchief is wound on the shaft and the surface of the material remaining in the embroidery frame is tightly stretched. The tightly stretched surface of

the material lies on the rear side of the frame, turned towards the path of the shuttle, and the needles 17 are disposed behind the surface of the material, at the side of the shafts 7. 5 The embroidery frame is so dimensioned that only the surface of the handkerchief to be embroidered remains free, whereas the whole of the remaining part is wound up, which has the advantage that a greater number of 10 handkerchiefs than formerly can be embroidered at one time. Moreover the stretching of a single piece of material can be done in a shorter time than the stretching of handkerchiefs hitherto.

15 I claim:

1. Apparatus for stretching the material for embroidering handkerchiefs in embroidery machines, comprising a plurality of frames for arrangement in series on the frame 20 of an embroidery machine and each having a shaft perpendicular to the embroidery machine needles and so arranged that an intermediate portion of a piece of material running in the direction of the row of needles 25 between each two needles working consecutively may be wound upon one of said shafts and so that between each of said shafts a strip may be left free for the embroidery, each of said shafts comprising a pair of longitudinally divided members one separable 30 from the other.

2. A stretching device of the class described comprising a frame for arrangement on the frame of an embroidery machine and 35 provided with parallel shafts mounted for rotation and provided with means to prevent backward rotation and also provided with tubes in which said shafts are concentrically arranged and the inner diameter of which is 40 greater than the diameter of said shafts to form annular spaces around the shafts, each tube being open on one side and each of said shafts comprising a pair of substantially semi-cylindrical members one separable from 45 the other.

3. Apparatus as claimed in claim 1, in which each of said several longitudinal frames secured on the machine frame is of oblong rectangular form and each frame is 50 provided with one of said parallel shafts arranged perpendicular to the long side of the frame, said shafts of the several frames being equally spaced apart and each frame also having stop devices to prevent backward 55 rotation of said shafts.

In testimony whereof I have hereunto set my hand this 29th day of January, A. D. 1927.

EMILE STRAUB.
